(57) **CLAIM**

The ornamental design for a chopping board as shown and described.

DESCRIPTION

FIG. 1 is a front, right and top perspective view of a chopping board, showing my new design;

FIG. 2 is a rear, left and bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a partial enlarged view thereof, taken from FIG. 1; and,

FIG. 10 is a partial enlarged view thereof, taken from FIG. 2.

The long dash-short dash broken lines depict enlargement boundaries that form no part of the claim. The evenly-spaced broken lines shown in broken lines in FIGS. 2 and 4 show portions of the chopping board that form no part of the claimed design.

1 Claim, 10 Drawing Sheets(56)
